DESIGN FOR AN ELECTRIC VAPORIZER

Joseph Robinson, New York, N. Y.

Application January 8, 1940, Serial No. 89,345

Term of patent 14 years

To all whom it may concern:

Be it known that I, Joseph Robinson, a citizen of the United States, residing at New York, in the county and State of New York, have invented a new, original, and ornamental Design for Electric Vaporizers, of which the following is a specification, reference being had to the accompanying drawing, forming a part thereof.

I claim:

The ornamental design for an electric vaporizer, substantially as shown.

JOSEPH ROBINSON.
